UNITED STATES PATENT OFFICE

ERWIN P. BANCROFT, OF BROOKLYN, NEW YORK, ASSIGNOR TO INTERNATIONAL COMMUNICATIONS LABORATORIES, INC., OF NEW YORK, N. Y., A CORPORATION OF NEW YORK

KEYBOARD TRANSMITTER

Application filed May 1, 1931. Serial No. 534,295.

My invention relates to improvements in keyboard transmitter mechanism for transmitting code signals, and more especially for use in connection with printing telegraphs.

5 In keyboard transmitters it has been customary when a key lever has been depressed to set up a code combination for transmission to lock either the key levers or the code bars, and maintain them in the locked condition 10 until the transmission of the signal has been completed. Under these conditions a second key lever cannot be depressed to set up a succeeding combination until the combination set up by the first key lever has been transmitted and the mechanism released.

The result is that very little time is allowed between the unlocking of the mechanism and the time at which transmission of the succeeding character signal should start for the 20 depression of the next key lever and difficulty is experienced by the operators in attaining a speed of operation closely approximating that at which the apparatus is set to operate.

25 The object of my invention is to eliminate this fault by providing a mechanism for reading off the code combination from the code bars at the beginning of the transmission period and thereafter leaving both the key and code bars free to be positioned in accordance with a new combination to be transmitted. I further provide means whereby the code combination to be transmitted after being read off from the code bars is 30 stored in the mechanism until the signals corresponding thereto have been transmitted.

Another object of my invention is to provide a starting mechanism such that the depression of a second key lever before the transmission of the signals corresponding to the first key lever depressed has been completed will condition the same to start the mechanism a second time even though the 45 second key lever be released before the completion of the first signal period. This allows the second set of signals corresponding to the second key depressed to follow the transmission of the first set of impulses without loss of valuable line time.

Still another object of my invention is to arrange the code bars operated by the key levers to have unrestrained movement in two directions free from any normal connection with the selector bars or other part of transmitting mechanism.

This provides a keyboard wherein the keys can be depressed rapidly and by a very light touch as friction is reduced to a minimum and the spring tensions to be overcome are 60 extremely small being only such as to normally hold the key bars out of engagement with the code bars.

Other features of my invention will be apparent in the description which follows.

Referring to the drawings:

Fig. 1 shows the starting mechanism;

Fig. 2 shows the essential features of the code signalling mechanism;

Fig. 3 is a modification in part of Fig. 2.

Referring to Fig. 1:

The shaft 22 upon which are mounted the various cams shown in Fig. 2 also carries a stop dog 32 arranged to engage a stop arm 34 pivoted at 36. This dog 32, for operating 75 the clutch, corresponds to stop "X" of Figs. 4 and 10 of United States Patent No. Re. 17,725 to F. G. Creed, granted July 8, 1930, although other forms of standard clutch mechanism may be used.

The stop arm 34 is operated by the counter-clockwise movement of the lever 38 about the pivot 39 under the influence of a link 40 connected to the universal bail 31 on the keyboard. This bail is shown pivoted at 85 points 45.

When the key lever 41 is depressed the projection 47 on the bail engages the inclined surface of the lever 40 at 48, causing the lever to rotate on the pivot 46 and thus causing the 90 operation of lever 38 and the engagement of the pawl 49 with roller 35 on arm 34. This pawl 49 is pivoted to the arm 38 at 50 and is held against the stop 51 by the tension spring 37.

When the pawl 49 comes into engagement with roller 35 the opposite end of the stop arm 34 is forced out of engagement with the stop dog 32, thus permitting the cam shaft 22 to rotate. During the clockwise rotation 100

of lever 38, that is when the key lever 41 is released, thus releasing the universal bail 31, the pawl 49 rotates about pivot 50 and does not depress roller 35.

5 A latch 44 pivoted at 54 is arranged to engage a projection 56 on stop arm 34 holding it out of engagement with the stop dog 32 whenever the stop arm is operated by the depression of roller 35. Pin 55 carried on the 10 clutch housing 32 is arranged to engage the bevelled surface 55 of latch 44 which causes the latch to unlock or disengage the projection 56 and allow the arm 34 to assume its normal position after the shaft 22 has rotated 15 only a small fraction of a revolution.

The purpose of this latch is to lock the stop arm 34 in a position so it will not engage stop dog 32 if the universal bail 31 is operated a second time before shaft 22 has 20 completed its first revolution.

An advantage of this arrangement when applied to a keyboard transmitter of this type is that, not only is it possible to operate a second key lever before the transmission 25 of the code impulse corresponding to the first key lever has been completed, but further that it is not necessary to hold the second key lever operated until the completion of the transmission of the first code combination. With such an arrangement it is possible to operate two key levers at an average speed in excess of five times the working speed of the transmitter, or three key levers at an average speed of approximately two 30 and one-half times the working speed, or four key levers at something over one and one-half times the working speed. While this advantage is appreciable for a large number of letters, it is, of course, understood 35 that over a period of time the average speed cannot exceed the normal operating speed of the transmitter. However, this mechanism will allow for a considerable unevenness in the operation of the keyboard and permit at 40 the same time the operator to approach very closely the operating speed at which the transmitter is set to operate.

Referring to Fig. 2, 42 represents one of 50 five code bars having notches cut in such a manner that the depression of any key bar or lever 41 will force them into the desired position in accordance with the code representing that particular key lever. The code bars are five in number in the arrangement 55 shown, although it should be understood that there will be one such for each element of the code with which the mechanism is designed to operate.

Thus, if the letter "A" key bar is depressed, 60 the first and second code bars may be moved to the right, and the third, fourth and fifth to the left. In front of each code bar is a lever or selector bar 2 all mounted on a pivot rod 3 supported in a cradle 5. In addition 65 to the five code bars there is a sixth or uni-

versal bar 31 (shown in Fig. 1) which serves to release the clutch mechanism and start the transmitter.

The cam shaft 22 carries at each end a cam 21 so positioned that as soon as the cam shaft is released and starts to rotate in the direction of the arrow, the cradle 5 pivoted at 6 will be forced downward by a projection on the cam 21 coming into engagement with the roller 4 carried by the shaft 3 upon which 75 are mounted the levers 2 which engage the code bars 42.

If one of the code bars is in front of its corresponding lever 2, the left-hand end of 2 will be prevented from moving, thus forcing 80 the right-hand end of this lever downward. If, however, the code bar is not in front of its associated lever 2, the left-hand end will move downward, while the right-hand end will be held in the position shown, by the 85 tension spring 14.

The shaft 22 carries two other cams 8 which engage rocker arms 18 pivoted at 19. The two arms 18 support a locking bar or bail 9 arranged to pass over or under the ends 90 of the levers 2 according to the position they have assumed. The operation of the bar 9 by cams 8 is such that when levers 2 have taken their positions in accordance with the selection represented by the particular key lever depressed, levers 2 will be locked in that position. Thus, those levers 2 in front of which a code bar 42 has been placed will have their extreme right-hand end locked in the downward position, while those in front of which no code bar has been placed will be locked in the position shown. Cam 8 is so arranged that levers 2 will remain locked until near the end of the revolution of the cam shaft 22 or until the completion of the 100 code signal.

Cam 21 allows cradle 5 to return to normal as soon as levers 2 are locked in their selected positions and thereby freeing all selector bars 2 from contact with code bars 42.

The shaft 22 also carries five cams 7 having detents or flat surfaces corresponding to the five elements of the code combinations. Co-acting with these five cams and the five levers 2 are five levers 12 pivoted on the bearing rod 10. The levers 12 are normally held in the position shown by the extensions on the levers 2 and the surfaces of cams 7.

During the revolution of the shaft 22, the lower extremity of the five contact operating levers 12 will tend to move to the left or toward the code bars 42, under the tension of springs 14.

Those levers 12 in front of which a projection of lever 2 is found will be restrained from moving, while those having the extension on lever 2 out of their path will be allowed to move. Any of the five levers 12 in operating moves its associated arm 26. These arms are rigidly mounted on a common shaft 125 130

27 upon which is also mounted the contact lever 16 carrying contact arm 60. If any of the lower ends of levers 12 move to the left, they will operate their respective arms 26 5 and move lever 16 in a counter-clockwise direction causing the tongue 60 to engage contact 61. Those levers 12 not permitted to move will allow lever 16 to move in a clockwise direction under influence of springs 28 10 causing the tongue 60 to engage contact 62. Since the five levers 12 operate in succession causing tongue 60 to engage contacts 61 and 62 in succession, these contacts will be closed in accordance with the code combination 15 representing the particular key lever depressed. In order that contact 62 may be closed after the signals representing each code combination have been transmitted a sixth lever 23 and a sixth cam 25 are provided. The cam has a detent or flat surface located so the lever 23 is allowed to rotate clockwise to close contact 62 when the shaft 22 is in its stop position.

The code bars 42 are provided with slots 25 100 which engage a stop 101 to prevent the bars from being moved out of their operative position with respect to the key levers 41.

The modification shown in Fig. 3 operates substantially the same as the apparatus shown in Fig. 2, except that in Fig. 3 the selector bars 2 control the operation of levers 12 through the medium of levers 77.

Corresponding parts of Fig. 3 are given the same reference numbers as in Fig. 2.

The operation of code bars 42 by key levers (not shown in Fig. 3) and the positioning of the selector bars 2 in their selected and non-selected positions is the same as in Fig. 2.

When the selector bars 2 move to their selected positions, the locking bail 9 is operated to hold them in that position. When those bars 2 whose ends 73 have been forced downward the projection 80 of bail 9 will pass over the surfaces 82 and hold them in their downward positions.

The selector bars 2 which have not been moved downward will be held in their normal positions by the projections 80 of the locking bail 9 moving into the notches 81 of the selector bars 2.

When the selector bars 2 are locked in their determined positions the cradle 5 is allowed to return to normal position thereby freeing the code bars 42, which may then be set to other positions.

When the portion 73 of the selector bar 2 moves downward, the lower end 76 of latch bar 77 pivoted at 78 moves inward under the influence of spring 87 and the upper end 80 moves outward and disengages extensions 90 of lever 12 to allow lever 12 to be controlled by cam 7 in the same manner as in Fig. 2. For those selector bars 2 which have not been operated, the latch 77 is not moved to release the portion 90 to allow lever

12 to be controlled by cam 7. The operation of levers 12 controls the contact lever 16 through the medium of a common member 91. The closing of the contact tongue 60 on contacts 61 or 62 will transmit signal combinations corresponding to the setting of the code bar.

What is claimed is:

1. A keyboard transmitter comprising a plurality of depressible key levers for setting up signal combinations, means for transmitting signals corresponding to the combination set up by the depression of one of said key levers, means under control of the signal transmitting means for rendering another of said key levers depressible for transmitting signals corresponding to combinations set up by its depression and before all the signals corresponding to the first combination have been transmitted.

2. A keyboard transmitter comprising a plurality of depressible key levers for setting up signal combinations, means for transmitting signals corresponding to the combination set up by the depression of one of said key levers, means under control of the signal transmitting means for rendering another of said key levers depressible for transmitting signals corresponding to the combination set up by its depression and immediately after the setting up of the first signal combination.

3. A keyboard transmitter for transmitting signals comprising a plurality of keys, means for controlling the starting of the transmission of said signals, means for locking said starting means when one of said keys is operated, means for unlocking said starting means after the transmission of impulses has started so it can again be locked by another key independent of the transmission of said signals.

4. A keyboard transmitter for transmitting signals comprising a plurality of keys, mechanism for controlling the transmission of said signals, means for starting said mechanism when one of said keys is operated, means for locking said starting means, and means for unlocking said starting means after the transmission of signals has started, so it may be locked again by a second key independently of the transmission of said signals started by the operation of the first said key.

5. A keyboard transmitter comprising a plurality of depressible key levers, a plurality of code bars engageable by said key levers when depressed, selector bars having no mechanical connection with said code bars, means for causing said code bars to become associated with said selector bars in combinations according to the key lever depressed, and transmitting contact operating means controlled by the selector bars.

6. A keyboard transmitter comprising a plurality of movable selector bars, a plurality of movable code bars entirely discon-

5 nected from said selector bars, means for moving said code bars in the path of said selector bars for controlling their movement and transmitting contact operating means controlled by the selector bars.

7. A keyboard transmitter comprising a plurality of movable selector bars, a plurality of code bars having unrestrained movement in two directions, means for moving 10 said code bars in one direction in the path of said selector bars and in another direction away from said selector bars, and transmitting contact operating means controlled by the selector bars.

15 8. A device comprising a plurality of code bars and corresponding selector bars mechanically disconnected therefrom, means for selecting a combination of said code bars, means for transferring the combination selected to said selector bars, a transmitter contact operating lever controlled by each selector bar, and means for controlling said operating levers in sequence in accordance with the combination transferred to said selector 25 bars.

9. A device comprising a plurality of movable code bars and corresponding movable selector bars mechanically disconnected 30 therefrom, means for positioning said code bars, means controlled by the positioning of said code bars to determine the position of said selector bars, transmitting contact operating means controlled by the selector bars, 35 and means to lock said selector bars in their determined positions so said code bars may be moved to other positions.

10. A device comprising a plurality of movable code bars and a plurality of movable selector bars, means for positioning said code bars, means to move said selector bars to positions determined by the positions of said code bars, and means to lock said selector bars in their determined positions so 45 said code bars may be moved to other positions.

11. A device comprising an operating mechanism, means for controlling the operation of said mechanism, means for operating 50 said controlling means to cause said mechanism to perform one complete operation, and means for allowing said controlling means to be again operated before the mechanism has completed its first operation so both operations will be continuous.

12. A device comprising an operating mechanism, means for starting the operation of said mechanism, means for stopping the 60 operation of said mechanism after it has performed one complete operation, means for operating said starting means to cause the operation of said mechanism, and means for allowing said starting means to be again operated before the performance of its first op-

eration to render the stopping means ineffective so both operations will be continuous.

13. Transmitting apparatus for electric telegraphs comprising a plurality of permutation elements, means for setting up said permutation elements in accordance with code combinations of signal impulses to be transmitted, selector elements corresponding to the permutation elements, a rotary cam member having a section for actuating the selector elements to set them in accordance with the setting of the permutation elements, means controlled by the selector elements and the rotary cam member for transmitting the code combination of impulses represented by the setting of the selector elements, and means including a lock controlled by the rotary cam member to lock the selector elements in set position and free the permutation elements for another setting during the transmission of the code combination locked on the selector elements. 70 75 80 85

14. A keyboard transmitter for transmitting signals made up of a starting impulse, a plurality of selecting impulses and a stop impulse, comprising a plurality of keys, permutation code mechanism set by the operation of any of the keys and controlling the combinations of selecting impulses to be transmitted, a driving shaft, a driven shaft, a single revolution clutch for coupling the shafts, means controlled by and during the rotation of the driven shaft to transmit the starting impulses, the selecting impulses as determined by the setting of the code mechanism and the stop impulse, a latch normally holding the clutch disengaged, means responsive to the operation of any key to operate the latch and allow the clutch to engage, means effective upon operation of the latch to lock 90 95 100 it in operated position, means controlled by the driven shaft to release the locking means before transmission of the stop impulse and allow the latch to return to normal position so that it may again be operated and locked in 110 response to the operation of any of the keys before completion of transmission of the selecting impulses. 110

15. A keyboard transmitter for transmitting signals made up of a starting impulse, a plurality of selecting impulses and a stop impulse, comprising a plurality of keys, permutation code mechanism set by the operation of any of the keys and controlling the combinations of selecting impulses to be 115 120 125 transmitted, a driving shaft, a driven shaft, a single revolution clutch for coupling the shafts, means controlled by and during the rotation of the driven shaft to transmit the starting impulses, the selecting impulses as determined by the setting of the code mechanism and the stop impulse, a latch normally holding the clutch disengaged, means responsive to the operation of any key to operate 130 135 the latch and allow the clutch to engage, 130

means effective upon operation of the latch to lock it in operated position, and means controlled by the driven shaft and operating during the transmission of the starting impulse to release the locking means thereby allowing the latch to return to normal position so that it may again be operated and locked in response to the operation of any of the keys before completion of the transmission of the selecting impulses.

16. A keyboard transmitter comprising a plurality of keys, a plurality of permutation bars set in different combinations by operation of the various keys, a universal bar invariably operated by the operation of any of the keys, selector bars corresponding in number to the number of permutation bars and pivotally mounted intermediate their ends, a rotary cam member started in rotation by operation of the universal bar and having a section for causing the selector bars to tilt in one direction or the other according to the setting of the permutation bars, a locking bar positioned under control of the rotary cam member to lock the selector bars in their tilted position, a series of successively operated sections on said rotary cam member corresponding respectively to the selector bars, and transmitter contact means operated under control of the successively operated sections as determined by the tilted position of the respective selector bars.

17. A keyboard transmitter comprising a plurality of keys, a set of permutation members variously positioned by the operation of the keys, a pivotally mounted cradle, a set of selector bars pivoted on said cradle, transmitter contacts, and a rotary cam set in operation upon actuation of any key and having a section for invariably rocking the cradle about its pivot thereby to cause the selector bars to assume positions determined by the setting of the permutation members and having a series of successively operative sections for controlling the operation of the transmitter contacts in accordance with the positioning of the selector bars.

18. A keyboard transmitter comprising a plurality of keys, a set of permutation members variously positioned by the operation of the keys, a pivotally mounted cradle, a set of selectors pivoted on said cradle, a rotary cam set in operation upon actuation of any key to rock said cradle about its pivot thereby to cause the selectors to assume set positions determined by the setting of the permutation members, a locking bar controlled by the rotary cam to lock the selectors in set position, transmitter contacts under control of the rotary cam and the selectors, and means to restore the cradle to normal position with the selectors locked in set position thereby to free the permutation members for re-positioning before transmission of the se-

lecting impulses represented by the setting of the selectors.

In witness whereof, I hereunto subscribe my name this 30th day of April, 1931.
